UNITED STATES PATENT OFFICE.

GODFREY M. S. TAIT, OF MONTCLAIR, NEW JERSEY, AND CARLETON ELLIS, OF WHITE PLAINS, NEW YORK.

PROCESS OF GENERATING AND REGULATING THE GENERATION OF POWER.

998,655.

Specification of Letters Patent. Patented July 25, 1911.

Application filed November 14, 1905. Serial No. 287,240.

To all whom it may concern:

Be it known that we, GODFREY M. S. TAIT, a British subject, residing in Montclair, Essex county, New Jersey, and CARLETON ELLIS, residing in White Plains, Westchester county, New York, have invented a certain new and useful Process of Generating and Regulating the Generation of Power, of which the following is a specification.

10 Our invention relates to a process of regulating the development of power in internal combustion engines, and particularly in engines operated on producer gas and similar gas of low or variable thermal value, or 15 comprising gaseous ingredients having quite different properties as regards self-ignition, flame-propagation, etc.

The methods heretofore employed for regulating the operation of internal combustion engines have all proved unsatisfactory. The "hit-and-miss" method of regulation produces excessive speed fluctuations, so that it is entirely impracticable in many cases, and in many of its forms is extremely 25 wasteful of fuel. All methods of regulating involving variation in the quantity of gas and air taken into the cylinder, such as throttling and variable opening or closing of the admission valve (the latter method 30 sometimes termed "variable cutoff") produce extreme variation in the compression pressure, such pressure increasing at different rates according to the total quantity of gas and air taken into the cylinder. Such 35 variation in compression is extremely detrimental as regards economy, for it is well known that for highest efficiency high compression is necessary, and obviously an engine which at light loads compresses only 40 to relatively low pressures, is uneconomical at such light loads and low compression pressures. Variation of the compression is particularly detrimental, however, in the case of engines operating on producer gas, 45 or similar gas of low or variable thermal value. Such gases require high compression to insure thorough and prompt ignition, or even to insure ignition at all. If the engine be regulated by varying the total 50 amount of fluid taken into the cylinder, it may easily, and frequently does, happen, that at light loads and low compression pressures ignition is uncertain or fails altogether. It is of course substantially impracticable to supply a richer fuel to an en-

gine when operating at light load than when operating at heavy load, and to do so would still further decrease the efficiency at light loads. The extreme of this disadvantage of varying the quantity of fluid taken into the cylinder is experienced when the engine is supplied with gas by a single producer the only, or substantially the only, function of which is to supply gas to that particular engine. Irregularities in the quality of gas furnished by the producer then produce their maximum effect, and if it happens, as is apt to be the case, that the producer furnishes the poorest gas when the engine is running on light load and with low compression pressure, the engine is apt to stop. When starting up such an engine, also, the gas from the producer is apt to be of especially low thermal value, and since the engine is then without load, usually, and its valve gear is adjusted so that the compression is low, it is often difficult to start an engine operating on producer gas. All of these difficulties we obviate by taking into the cylinder substantially the same total quantity of fluid at all times, regulation being effected by varying the richness of the charge by automatically varying the amount of air admitted, or by admitting and similarly regulating a neutral diluent gas, such as products of combustion, but the total quantity of thoroughly mixed gases or vapor and gases admitted always being the same. The compression is then substantially the same at all loads. To compensate for the variation in the rate of flame propagation with varying amounts of air or neutral diluent gas in the charge, we automatically vary the point of ignition to correspond with the variation in the amount of diluent. In this way we are able to employ very high compression pressures at all loads, with resulting gain in economy, and to realize nearly the same economy at light loads as at full loads.

In the course of our work with high compression engines, it has been noted that fuels which are not homogeneous as to combustible ingredients are not as advantageous for engine purposes as fuels containing substantially only one combustible, particularly in high-compressing engines. In such engines, gases containing considerable percentages of hydrogen appear particularly disadvantageous, the hydrogen being apt to ignite spontaneously during the compression

stroke, producing excessive back pressure against the piston, causing the engine to do negative work, and greatly lowering its efficiency. Such trouble is termed "preignition". When using a fuel containing ingredients, such as hydrogen, which tend to cause preignition, or irregular combustion (as when one or more ingredients burn largely or entirely before the others), we 10 commonly use a mixture of air and products of combustion as a diluent, the products of combustion having a marked effect in holding back ignition of hydrogen or other gases tending to ignite spontaneously under high 15 compression. When the gas used is homogeneous or nearly so, we may use air alone as the diluent.

The objects of our invention are, to regulate the development of power in internal 20 combustion engines in an improved manner, to obtain higher economy of operation at all loads, but particularly at light or variable loads, to avoid variation in the compression with variation in load or speed, to 25 prevent pre-ignition, to insure complete ignition, and to permit the use of fuel of low and variable thermal value.

In the accompanying drawings we illustrate apparatus in which our said process 30 may be carried out, the same comprising an internal combustion engine which in general is of ordinary construction.

In the said drawings: Figure 1 is a central vertical sectional view of the engine; 35 Fig. 2 is a side view and partial section of the feed pipes, mixing device, and automatic regulating device; and Fig. 3 is a detail view of the mechanism for regulating the point of ignition.

40 In the said drawings, 23 designates the engine cylinder, 22 the jacket therefor, 13 the clearance or compression space, 12 the piston, 11 the connecting rod, and 14 the crank.

45 1 and 2 designate, respectively, exhaust and admission valves, which may be operated by any suitable valve gear, that illustrated comprising a rocking lever 4 operated, through suitable connections, by a cam 9, 50 which may be understood to be driven in the usual way from the crank shaft by means of gearing. The rocker 4 alternately presses in first one of said valves and then the other, and is adjustable longitudinally 55 to vary the opening and closing of the valves. The operation of this valve gear is obvious and requires no further description.

60 3 designates a conventional electric igniting device, operated by a link 16 from an eccentric on shaft 18, which shaft may be understood to be driven by suitable gearing from the crank shaft, as is common in engines of this type.

65 6 designates the admission port of the cylinder, and 7 the discharge port thereof.

24 designates the gas supply pipe of the engine, and may be understood to be connected to a gas producer of ordinary type.

25 is a pipe supplying the air for combustion and also for dilution of the charge for regulation. Said pipes are provided with ordinary regulating valves, adjustable by hand, numbered 20 and 19 respectively. Pipe 25 terminates in a collar 5 surrounding pipe 24, the latter being perforated within said collar, so that the fluid from pipe 25 is mingled thoroughly with the gas entering through pipe 24. Regulation of the amount of fluid from pipe 25 flowing to pipe 24 is effected by a valve 21 operated automatically by a speed governor 8, which may be understood to be driven from the crank shaft or other suitable part of the engine. This valve may also control a port 26, indicated in dotted lines in Fig. 2, connected to a source of supply of products of combustion, such for example as the exhaust pipe of the engine.

The eccentric on shaft 18 which operates the igniter 3 through the link 16, is engaged by a spiral spline 17 on said shaft, and an automatic governor 27, which will be understood to be driven from some moving part of the engine, such as the crank shaft, is arranged to move shaft 18 longitudinally, thus varying the angular advance of the eccentric and the time of ignition in accordance with, and in exact relation to, variation in the amount of diluent admitted through valve 21, the advance of the spark corresponding to the decrease in richness of the mixture admitted.

The method of regulating the development of power is as follows: Supposing the engine to be operating under maximum load, valve 21 will be substantially half open as regards passage of air from pipe 25 to pipe 24, and a charge of maximum richness will enter the engine cylinder during each admission stroke, and will there be compressed, ignited, and caused to expand, in the ordinary way. If now the load on the engine be reduced, the centrifugal governor 8 will open valve 21 still farther, admitting more air from pipe 25 to pipe 24, and also opening port 26 and admitting products of combustion, which mingle with the air, and gas, diluting the latter and retarding the combustion of hydrogen and similar substances in the final ignition of the charge. The total amount of fluid taken into the cylinder remains the same, it will be seen, whatever the load, and therefore the compression is substantially the same at all loads; but the richness of the charge will be decreased.

The rate of combustion being thereby changed, the governor 27 automatically advances the point of ignition to compensate for the decreased speed of combustion. Conversely, when the load on the engine is again

increased, the automatic governors will reduce the amount of diluent admitted and will retard ignition to correspond with the increased rate of combustion of the charge.

- 5 It will be seen therefore, that by the action of the two automatic governing devices the character of the charge and the point of ignition will be varied to suit the load on the engine and to maintain constant speed, 10 without varying the compression. We are enabled, therefore, to employ very high compression at light loads as well as at intermediate and heavy loads, and to employ fuel of low thermal value at all loads, the ignition of such fuel being relatively certain because of the very high compression employed. This compression we prefer to be from say 9½ to 16 atmospheres, preferably not below 11 atmospheres. At this high 15 compression mixtures which cannot be depended upon to ignite at lower pressures ignite readily.

Producer gas such as we especially contemplate using has for its principal combustible constituent, carbon monoxide; but many types of producers or generators of fuel gas produce large quantities of hydrogen as well, giving rise to the pre-ignition trouble above mentioned when the engine 20 operates with high compression. When the gas used contains little or no hydrogen, we commonly employ air alone as the diluent, it being understood that any excess of air mixed with the gas above that required 25 for combustion is a mere diluent, and is substantially neutral. When the gas used contains considerable quantities of hydrogen or other readily igniting gases which tend to give rise to pre-ignition troubles, we prefer- 30 ably mix more or less products of combustion with the air. Such products of combustion may be drawn from the exhaust pipe of the engine, or from the stack of any convenient furnace or the like, and are prefer- 35 ably cooled before being mixed with the air and gas, on account of the greater density at low temperatures. The specific heat, by volume, of products of combustion is relatively high, as compared with air, and such 40 products exert a marked influence tending to hold back the ignition of hydrogen and like constituents which tend to ignite prematurely under the conditions of heat and pressure prevailing in the engine 45 cylinder during compression; such holding back being due, probably, in great measure to the presence of considerable quantities of carbon dioxide in the products of combustion. By properly diluting the charge to corre- 50 spond with the load on the engine, without varying the amount of the charge, by correspondingly varying the point of ignition, and when necessary holding back the ignition by employing greater or less quantities 55 of products of combustion in the charge, we

are able to insure proper ignition, without so much combustion before the piston reaches the end of its compression stroke as results in excessive back pressure on the piston and the doing of negative work; and thereby we 70 are enabled to use, at all loads, very cheap fuel gas of low thermal value, or containing considerable proportions of ingredients having widely different rates of combustion, and are thus enabled to obtain very high com- 75 mercial and thermo-dynamic economy.

Hitherto it has usually been considered that the effect of products of combustion in the charge of an explosion engine is highly prejudicial, as tending to make ignition irregular or to prevent it altogether, and very often elaborate measures have been taken to produce very complete scavenging of the cylinder; but we have found that the objections heretofore found to unavoidable or 80 unintentional retention of a portion of the products of combustion within the cylinder do not apply when the products of combustion are used in carefully regulated proportions and are thoroughly mixed with the 85 entering air and gas, but that to the contrary very decided advantages result from the proper mixing of suitably regulated proportions of products of combustion with the charge, as before stated. 95

In the case of engines which operate by the injection of fuel into the cylinder or combustion chamber of the engine, the products of combustion for diluting the mixture and retarding combustion will be introduced, ordinarily, with the entering charge 100 of air.

What we claim is:—

1. The process of generating power and of regulating the same, in internal combustion engines, which consists in drawing into the engine cylinder successive charges of substantially uniform amount comprising producer or like gas, air for combustion and a diluent gas all substantially uniformly admixed with each other, mixing outside of said cylinder air and products of combustion together to make the said diluent gas of the charge and then mixing the same with the remainder of the charge, varying the proportion of diluent in the charges in accordance with the work required, compressing the mixture, and igniting the same at a variable point corresponding to the amount of diluent present. 105

2. The process of generating power and of regulating the same, in internal combustion engines, which consists in drawing into the engine cylinder successive charges of substantially uniform amount comprising producer or like gas, air for combustion and a diluent gas all substantially uniformly admixed with each other, mixing outside of said cylinder air and products of combustion together to make the said dilu- 110

115

120

125

130

ent gas of the charge and then mixing the same with the remainder of the charge, varying the proportion of diluent in the charges in accordance with the work required, compressing the mixture, and igniting the same at a variable point corresponding to the rate of flame propagation through the mixture.

3. The process of operating and regulating the speed of internal combustion engines which consists in diluting and thoroughly admixing the entering charge of mixed air and combustible with a diluent mixture of air and products of combustion in variable amount to form a charge of constant bulk, compressing the diluted mixture and causing combustion thereof.

4. The process of operating and regulating the speed of internal combustion engines which consists in diluting and thoroughly admixing the entering charge of mixed air and combustible with a diluent mixture of air and products of combustion in variable amount to make a charge of constant bulk, compressing the diluted mixture and igniting the same at a variable point corresponding to the amount of diluent.

5. The process of operating and regulating the speed of internal combustion engines which consists in diluting and thoroughly admixing an entering charge of air and combustible with a mixture of air and products of combustion, in variable amount, to make a charge of constant volume, com-

pressing the mixture and causing the combustion thereof.

6. The process of operating internal combustion engines which consists in diluting and thoroughly admixing an entering charge of air and combustible with a mixture of air and products of combustion, compressing the mixture and causing combustion thereof.

7. The process of operating internal combustion engines which consists in introducing therein a mixture of air and products of combustion with a mixture of air and combustible uniformly admixed, and compressing the mixture and causing combustion thereof.

8. The process of operating internal combustion engines and regulating the speed thereof, which consists in introducing therein a mixture of air and products of combustion, uniformly admixed with a mixture of air and combustible, the products of combustion being introduced in variable quantity according to the work desired, compressing the mixture and causing combustion thereof.

In testimony whereof we hereunto affix our signatures in the presence of two witnesses.
